UNITED STATES PATENT OFFICE.

JAMES W. JOHNSON, OF CHICAGO, ILLINOIS.

FIRE-ALARM BOX.

SPECIFICATION forming part of Letters Patent No. 621,093, dated March 14, 1899.

Application filed December 7, 1896. Serial No. 614,725. (No model.)

To all whom it may concern:

Be it known that I, JAMES W. JOHNSON, a citizen of the United States, residing at Chicago, in the county of Cook and State of Illinois, have invented certain Improvements in Fire-Alarm Boxes, of which the following is a specification.

My invention relates to signaling apparatus and may be applied to such, for example, as that shown and described in the patent to J. J. Ruddick, No. 553,873, dated February 4, 1896.

The object of my invention is to provide a device for controlling such apparatus under abnormal conditions.

I have illustrated my invention in the accompanying drawings, wherein—

Figure 1 is a view of a non-interfering signaling apparatus before my invention has been added. Fig. 2 is a view of a non-interfering signaling apparatus provided with my invention and with parts omitted. Fig. 3 is a view similar to Fig. 2, the position of the parts being varied. Fig. 4 is an end view of the non-interfering magnets, showing the armature for controlling my device. Fig. 5 is a view of a modified form of my invention. Fig. 6 is a view similar to Fig. 5 with the parts differently disposed.

Like letters refer to like parts throughout the several figures.

Fig. 1 shows a successive non-interfering signaling apparatus somewhat similar to that described in the Ruddick patent above referred to, and to which patent reference may be had for a detail description, as such apparatus is no part of my invention. I will describe this device briefly in order that my invention may be readily understood. This apparatus, as shown in Fig. 1, consists of an actuating-train of gears actuated by the spring A. This spring is connected with the gear A', provided with the annular projecting flange A², said flange being cut away so as to form the openings A³. The locking-lever B is pivotally connected to the frame carrying the actuating-train and is provided with the projection B', which fits into the opening A³ when the mechanism is at rest, but which bears upon the outer surface of the flange A² when the mechanism is in operation. The starting-lever B⁴ is pivoted to the frame and

is adapted to move the locking-lever so that the pin B' is removed from the opening A³. A non-interfering magnet C is mounted upon the frame. A controlling-lever C' is pivoted at C² to the frame and is provided with the armature C³, opposed to the core of the magnet C. When the arm or lever C' is retracted by the spring C⁴, the armature C³ is moved far enough away from the magnet so as not to be attracted when the magnet is energized. This controlling-lever C' is provided near its lower end with a pin C⁵, the extreme lower end C⁶ of said lever being bent outwardly, as indicated, so that when in a predetermined position it will be engaged by the pins C⁷ on the gear C⁸, the engagement between said end C⁶ and said pin causing the controlling-lever to be moved so that the armature is in proximity with the core of the magnet. This controlling-lever C' is provided near its middle with a pin C⁹. The locking-lever B is provided at its end with the offset or projection B⁵, which engages the pin C⁹ when the controlling-lever is in the position shown in Fig. 1 and the projection B' is opposite one of the openings A³, thereby preventing said projection B' from entering said opening. The end of the lever B is provided with a beveled surface B⁶, which engages the pin C⁹ as the lever B moves downwardly, thereby moving the controlling-lever C' to a position where the end C⁶ will be engaged by the pin C⁷. Two contacts D D' are located in the main circuit and are normally held together by means of the circuit-controlling lever D². This lever D² is provided with a projection D³, which engages the lower spring-contact D', said lever being provided with the arm D⁴, which engages the pin C⁶. This circuit-controlling lever is opposed to the number or signaling wheel E, which is connected through the actuating-train with the spring A. This number or signaling wheel is provided on its periphery with teeth which engage the circuit-controlling lever when the mechanism is in operation, thereby moving said lever so as to make and break the circuit, and thus operate the receiving instruments at the central station. The flange A² of the wheel A' is provided with the pin A⁴, which engages the rear end A⁵ of the circuit-controlling lever when the projection B' is in the opening A³, thereby holding it in such a

position that the contacts D and D' are together.

If when the signaling apparatus shown in Fig. 1 is operated the non-interfering magnet 5 fails to hold the armature C³ during its free periods—i. e., when not held mechanically against the force of spring C⁴—the mechanism will continue running without transmitting a signal until the spring A runs down, 10 because the point B³ engages the pin C⁹. This occurs when the circuit remains open or the current strength remains too weak to energize the magnet sufficiently. In Fig. 2 I have 15 shown one form of my device which when added to the mechanism shown in Fig. 1 will prevent the mechanism from running down under such conditions and which will not affect its operation when the circuit is in proper condition. In order to produce this result, 20 I have added to the device shown in Fig. 1 the arm G, pivoted to the frame at G' and provided with the projection G², which engages the pin G³, so as to limit the motion of said arm. This arm is connected to an armature 25 G⁴, associated with the magnet C. Said armature is pivoted to the frame at G⁵. (See Fig. 4.) A lever G⁶ is pivoted to the arm G at G⁷ and is provided with a projecting end G⁸, to which is connected a spring G⁹. A pin 30 H is connected with the locking-lever B, the lever G⁶ projecting downwardly between said pin and the pin C⁹.

In Figs. 5 and 6 I have shown another construction of my device. In these figures the controlling-lever C' is divided, the lower end being pivoted to the frame at C², while the armature C³ is carried by a separate arm I, pivoted at I'. Connected to the upper end of the controlling-lever C' is a latch or dog I², 40 which is adapted to engage the end of the lever I. Pivotaly connected with the locking-lever B is an arm J, provided with an upwardly-projecting end adapted to engage the lever I. This arm J is provided at its lower 45 end with the branches J' J². The branch J' is provided with the projection J³, adapted to be engaged by the pin C⁹ on the controlling-lever C'. The branch J² is shaped so that its 50 end will engage the pin C⁹ when the lever C' changes its position from that shown in dotted lines in Fig. 5 to that shown by full lines, and the parts are so arranged that in changing position the pin will move the arm J² to the right out of its path and then engage the projection J³, at the same time causing the upper 55 end of the arm J to move to the left.

I have described two different forms of my device; but it is evident that other constructions than those herein shown may be used to 60 perform the same result. The constructions herein shown are sufficient to explain my invention, and I do not consider it necessary to show all the forms by which the same result may be obtained. I therefore do not wish to 65 be limited in any particular by the form, construction, and arrangement of the parts as

herein shown and described, nor to the application of it to any such device as shown herein.

The use and operation of my invention are as follows: Fig. 1 shows a successive non-interfering signaling device without my invention. A series of these signaling devices is connected to one circuit, and the mechanism is so constructed that the several instruments will not interfere with each other even if operated at the same time, the several devices giving their signals under these conditions one after the other. When it is desired to send in a signal, the signaling-lever B⁴ is moved so as to move the locking-lever B toward the magnet C, thereby moving the projection B' out of the opening A³ and releasing the actuating-train. If the normal current flows through magnet C, the armature C³, which is in proximity to said magnet, will be held in position as indicated in dotted line. The signal-wheel E now rotates, and the circuit-controlling arm D² being disengaged from pin A⁴ is moved up and down by means of the teeth of said wheel, thereby making 85 and breaking said circuit, so as to transmit the signal to the central station. When the circuit is completed, the armature C³ is held against the force of spring C⁴ by the magnet C, and when the circuit is broken by the operation of this number-wheel the end of arm D⁴ of the lever D² engages the pin C⁵, and thus prevents the armature and lever C' from assuming the position shown by full lines in Fig. 1. The projection B' now rests upon the 100 outer surface of flange A². When, however, one of the openings A³ comes opposite said projection, the projection will enter the opening and the lever B will return to its normal position, thereby locking the mechanism 105 from further movement. If when this instrument is started some other instrument is in operation, the circuit will be interrupted by such other instrument before the controlling-arm D² drops off the first tooth of the 110 signaling-wheel, as the period of time necessary to bring the arm down upon the first tooth after the mechanism is started exceeds the longest closure of the circuit made by any of the instruments when in operation. Under 115 these conditions the magnet C will fail to hold the armature C³ and the controlling-arm C' will be retracted by the spring C⁴ to the position shown in full lines in Fig. 1. When in this position, the pin C⁵ engages the arm D⁴ 120 of the circuit-controlling lever and prevents it from falling into the notches on the signal-wheel E and breaking the circuit at D and D'. The parts will then be in position shown in full lines, Fig. 1. The actuating-train continues to operate until one of the openings A³ comes beneath the projection B'. Said projection then enters the opening and the lever B is lowered, the beveled surface B⁶ engaging the pin C⁹ and moving the lower end of 130 lever C' outwardly. The downward movement of lever B is stopped by the engage-

ment of projection B⁵ and pin C⁹. The projection B' is thus held from entering opening A³ far enough to stop the train and the mechanism continuing to operate raises lever 5 B. Meanwhile the pin C⁷ on wheel C⁸ engages the end C⁶ of lever C' and moves the armature C into proximity to the poles of the magnet, where it will be held, if said magnet is properly energized. If there is still another 10 instrument transmitting a signal, it will not be held, and the lever C' will be again released and the operation above described will be repeated. If, however, there is no other instrument in operation and the circuit remains 15 closed, the lever C' will be held in its dotted-line position and the circuit-controlling arm D² will be free to drop into the notches on the number-wheel and transmit the signal. If the 20 circuit is open when the instrument is operated and remains open, or if the magnet C is not sufficiently energized to hold the armature, either of which would be an abnormal condition, and it is evident of course that there might be other abnormal conditions, 25 the mechanism will continue to operate until the spring A has run down. When my invention is attached, as shown in Fig. 2, it in no manner interferes with the operation of the mechanism when the circuit is in its normal 30 condition. If the circuit is open, the arm G⁶ projects between the pin C⁹ and H, and hence when the opening A³ comes opposite the projection B' the movement of lever B causes the arm G⁶ to move the controlling-lever C', so that the projection B⁵, instead of 35 engaging the pin C⁹, is allowed to pass by said pin, thus allowing said lever B to move to its locking position. If before the actuating-train has moved one of the openings A³ opposite the projection B' the circuit is completed, the armature G⁴ will be attracted and will move the arm G⁶ upwardly, so that instead of 40 engaging the pin C⁹ its end rests upon said pin. When said arm is in this position, it does not engage the pin C⁹ when the lever B moves downwardly, and hence the pin C⁹ engages the projection B⁵, so as to prevent the lever B from moving into its locking position, and the train continues to operate. It will 45 therefore be seen that if the current remains insufficient from the time the mechanism is started until the projection B' is brought opposite one of the openings A³ (an abnormal condition) it will be stopped; but if at any 50 time during this period the current is restored the instrument will continue to operate the same as it would without my device.

The operation of the device, as shown in Figs. 5 and 6, is as follows: If there is another 55 instrument in operation when the signaling-lever is moved, the controlling-arm C' will take the position shown in full lines, Fig. 5. The pin C⁹ is shown as engaging the projection J³ and the upper end of the lever J in a position where it will be engaged by the lever I when the magnet C is energized. If the circuit is open, said magnet, of course,

will not be energized, and when the projection B' comes opposite an opening A³ the lever B' will move downwardly. The arm J now swings about its pivot and moves lever C' outwardly, so that the end of lever B will pass the pin C⁹ and allow said lever to take its locking position. If, however, there should be a closure of the circuit, the arm I will engage the upper end of the arm J and move it to the position shown in Fig. 6, the pin C⁹ being then released from the projection J³. In moving the arm J the magnet attracts the armature against the force of the spring C⁴, so that the pin C⁹ passes projection J³ by 75 slightly moving lever C'. If now the lever B moves downwardly, its beveled surface engages the pin C⁹, thereby moving the lever C' to a position where it will be engaged by the pin C⁷. The end B⁵ of lever B also engages said pin, so as to prevent said lever from moving to its locking position. The pin C⁷ on the wheel C⁸ then engages the end of the lever C' and moves its upper end, carrying the latch I² toward the magnet. The engagement of this lever with the arm I moves the armature C³ in proximity to the magnet, where it will be held, if the magnet is properly energized. The latch I² when engaged 90 by the arm I moves about its pivot and permits the two parts to be locked together, so that after being released by the pin C⁷ the part I, if the armature is attracted, will hold the lever C' in position. It will thus be seen that the latch I² is a means of detachably attaching the lever C' and the arm I together, the movement of said latch allowing the proper connection to be made. The mechanism will therefore continue to operate and if the circuit is in the proper condition the signal will be transmitted.

In Figs. 5 and 6 I have shown the controlling-lever as divided. In other words, I have shown what may be called a "two-part" controlling-lever, the upper part carrying the armature.

It is possible to stop one or more boxes in operation by simply holding the circuit open a predetermined time at any point.

The device will operate on any signaling period during which the magnet lacks sufficient energy to retain the armature.

I have spoken of the "signal-wheel;" but of course I do not wish to be limited by the use of that term in my description and claims to that particular construction but to the equivalent thereof, as other numbered devices, so to speak, could be used to control the circuit making and breaking device quite as well as a signaling-wheel. I have also spoken in the claims of "arresting the action of the signaling device," meaning by those words to include the idea not only of stopping the action but also and preferably of arresting or suspending it, so that it is free to begin operations again when the action of arresting it ceases.

My apparatus is not necessarily confined to a use in connection with non-interference

boxes or succession-boxes, though doubtless it is particularly applicable to such and is shown in relation to such in the drawings and description. There might be systems in 5 which the boxes would be controlled in a sense from the central station. For example, it might be desirable to set the boxes so as not to give a signal at the central station when the central station was out of connection, perhaps having been switched out on account of the absence of the person in charge. In such case, as well as in other cases above referred to, the motor mechanism should, however, be stopped.

15 I have described my invention as operating on an open circuit; but it is of course evident that it may operate on circuits which have been weakened or decreased below a predetermined strength or otherwise made 20 abnormal.

I claim—

1. In a signaling apparatus, the combination of a starting device, motor mechanism responsive to the starting device, a signaling 25 device adapted to be operatively connected with said motor mechanism, a signal-arresting device, a motor-stopping device independent of the length of time the motor is in operation and normally held in an inoperative 30 position, but adapted to be rendered operative in response to abnormal conditions.

2. In a signaling apparatus, the combination of a starting device, motor mechanism responsive to the starting device, a signaling 35 device adapted to be operatively connected with a motor mechanism, a non-interference device, a signal-arresting device, an electrically-controlled motor-stopping device normally inoperative after the motor has been 40 started and before the mechanism has begun to send in its signal, but responsive to abnormal 55 conditions.

3. In a signaling apparatus, the combination of a starting device, motor-mechanism responsive to the starting device, a signaling device adapted to be operatively connected with the motor mechanism, a non-interference magnet, an armature associated therewith, a connection between said armature and the motor 50 mechanism whereby the armature is mechanically moved in proximity to the non-interference magnet, and a motor-stopping device inoperative while the motor is operated under normal conditions, but adapted to be rendered operative by abnormal conditions of the circuit.

4. In a signaling apparatus, the combination of a starting device, motor mechanism responsive to the starting device, a signaling device comprising two parts, one a circuit making and breaking device, the other a signaling-wheel to control the circuit making and breaking device, a signal-arresting mechanism to control the circuit making and breaking 65 device independent of the signaling-wheel, an electrically-controlled motor and signal-wheel stopping device held in an inoperative

position while the motor is in operation under normal conditions of current and adapted to be moved to an operative position in response 70 to abnormal conditions.

5. In a signaling apparatus, the combination of a starting device, motor mechanism responsive to the starting device, a signaling device comprising two parts, one a circuit making and breaking device, the other a signaling-wheel to control the circuit making and breaking device, a non-interference mechanism to control the circuit making and breaking device independent of the signaling-wheel 80 and without stopping the motor mechanism, and a motor and signaling-wheel stopping device inoperative at all times when the motor is operating under normal conditions, and independent of the length of time said motor is 85 in operation, but adapted to be brought into action to stop said motor by the presence of abnormal conditions.

6. In a signaling apparatus, the combination of a starting device, motor mechanism responsive to the starting device, a signaling device adapted to be operatively connected with a motor mechanism, a non-interference device comprising a magnet, a signal-arresting device, and an electrically-controlled motor-stopping device held inoperative under normal 95 electrical conditions at all times during the operation of the motor, but responsive to abnormal conditions and comprising in part the magnet of the non-interference device. 100

7. In a signaling apparatus, the combination of a starting device, motor mechanism responsive to the starting device, a signaling device comprising two parts, one a circuit making and breaking device, the other a signaling-wheel to control the circuit making and breaking device, a non-interference mechanism containing a magnet, a signal-arresting mechanism to control the circuit making and breaking device independent of the signaling-wheel and without stopping the mechanism, and a motor and signaling-wheel stopping device inoperative at all times while the motor is in operation and during the normal condition of the signaling-circuit, said stopping device constructed so as to be responsive to abnormal conditions and containing the magnet of the non-interference mechanism. 110 115

8. A signaling apparatus comprising an actuating-train, a non-interference magnet, a non-interference signaling apparatus operated thereby, and an electrically-controlled stopping device associated with said apparatus normally inoperative during the operation of the motor while the conditions of the circuit are normal, but adapted to be brought into operation under abnormal conditions and stop said apparatus before the train runs down. 120 125

9. A signaling apparatus comprising an actuating-train, a non-interference magnet, a non-interfering signaling apparatus operated thereby, a device associated with said apparatus and adapted to stop it at a predeter- 130

mined time when the apparatus is operated under abnormal conditions, a connection between said device and said non-interference magnet, said connection being such that if said magnet is energized during any part of a signal-making period of the signaling apparatus, said device is moved to an inoperative position during said entire signal-making period.

10 10. A signaling apparatus comprising an actuating-train, a locking-lever therefor, a circuit-controlling mechanism, a non-interference magnet, a controlling-lever, an armature for said magnet connected with said controlling-lever, a stopping mechanism associated with said controlling and locking levers and adapted when the apparatus is operated under abnormal conditions to connect said controlling and locking levers so that said 15 controlling-lever will be moved to a position where it will not be engaged by said locking-lever, and a connection between said stopping mechanism and said magnet whereby said stopping mechanism is rendered inoperative when said magnet is energized.

11. A signaling apparatus comprising an actuating-train, a locking-lever, a circuit-controlling mechanism, a non-interference magnet, a two-part controlling-lever having outer 20 locking ends, one part of said lever provided with an armature adapted to be acted upon by said magnet, a stopping mechanism associated with said controlling and locking levers and adapted, when the apparatus is operated under abnormal conditions, to connect said locking-lever and controlling-lever so that said controlling-lever will be moved by the movement of said locking-lever, to a 25 position where it will not be engaged by said locking-lever, and a connection between said stopping mechanism and said magnet whereby said stopping mechanism is rendered inoperative when said magnet is sufficiently energized.

12. A signaling apparatus comprising a magnet, a starting device, motor mechanism responsive to the starting device, a signaling device adapted to be operatively connected with the motor mechanism, a motor-stopping 30 device responsive to abnormal conditions, and a connection between said motor-stopping device and said magnet whereby a momentary excitation of said magnet during any part of a signal-making period of the signaling ap-

paratus causes said motor-stopping device to 55 be moved to an inoperative position during such period.

13. A signaling apparatus comprising a successive non-interfering mechanism provided with a locking-lever, a controlling-lever and 60 a non-interference magnet; an arm pivotally connected with said locking-lever and adapted to engage said controlling-lever when the apparatus is operated under abnormal conditions, an armature associated with said magnet and connected with said arm in such a manner that the arm is disengaged from said controlling-lever when said magnet is sufficiently energized.

14. A signaling apparatus comprising a successive non-interfering mechanism provided with a locking-lever, a non-interference magnet and a two-part controlling-lever, the two parts of which are provided with interlocking ends, an armature connected with one part 75 of said lever and associated with said magnet; an arm pivotally connected with said locking-lever, and having a projection which is associated with the armature end of said controlling-lever, said arm provided with two 80 branches one of which is adapted to engage a projection on said controlling-lever, when the locking-lever is raised and the circuit is broken, and cause it to engage the other branch of said arm, and a projection on said 85 latter branch which engages the projection on the controlling-lever and holds the parts in position.

15. In a signaling apparatus, the combination of a starting device, motor mechanism 90 responsive to the starting device, a signaling device adapted to be operatively connected with a motor mechanism, a signal-arresting device, motor-stopping mechanism adapted to stop the motor after the proper signal has 95 been transmitted, an engaging device adapted to engage said motor-stopping mechanism, and prevent it from acting to stop the motor until the proper signal has been transmitted, and a controlling device associated with said 100 engaging device and adapted to render it inoperative under abnormal conditions of the circuit.

JAMES W. JOHNSON.
